OTHER PUBLICATIONS

Japanese Patent Office Document HJ19003319, dated Mar. 2007.
(Continued)*Primary Examiner* — Paula Allen Greene(74) *Attorney, Agent, or Firm* — Sterne, Kessler, Goldstein & Fox P.L.L.C.(57) **CLAIM**

The ornamental design for earphones, as shown and described.

DESCRIPTION

FIG. 1 is a front view of earphones showing the claimed design;

FIG. 2 is a rear view thereof;

FIG. 3 is a top view thereof;

FIG. 4 is a bottom view thereof;

FIG. 5 is a right side view thereof; and,

FIG. 6 is a left side view thereof.

1 Claim, 6 Drawing Sheets# US D980,185 S
